UNITED STATES PATENT OFFICE

165,489

COMBINED JAR AND COVER OR SIMILAR ARTICLE

Stanley J. Shepard, Laguna Beach, Calif.

Application March 9, 1951, Serial No. 14,436

Term of patent 7 years

(Cl. D58—25)

To all whom it may concern:

Be it known that I, Stanley J. Shepard, a citizen of the United States, residing at Laguna Beach, State of California, have invented a new, original, and ornamental Design for a Combined Jar and Cover or Similar Article, of which the following is a specification, reference being had to the accompanying drawing, forming a part hereof.

Figure 1 is a side elevational view of a combined jar and cover or similar article, showing my new design;

I claim:

The ornamental design for a combined jar and cover or similar article, as shown.

STANLEY J. SHEPARD.
